FIG. 1

FIG. 2

FIG. 3

INVENTOR
F. A. NOETZLI

BY *Wright & Chase*

ATTYS.

UNITED STATES PATENT OFFICE.

FRED A. NOETZLI, OF BERKELEY, CALIFORNIA.

DAM.

Application filed October 23, 1920. Serial No. 418,897.

To all whom it may concern:

Be it known that I, FRED A. NOETZLI, a citizen of Switzerland, residing at Berkeley, in the county of Alameda and State of California, have invented new and useful Improvements in Dams, of which the following is a specification.

This invention relates to improvements in dams, particularly those of the multiple arch type, and the primary object of the invention is to provide a dam of this type, which will be more safe, reliable, and durable and easier and less expensive to build than dams such as heretofore constructed.

Heretofore in multiple arch dams, the place of greatest weakness and uncertainty with regard to strength has been in the buttresses and although the stresses in the arches proper may be accurately determined by means of the theory of the elastic arch, the stability of the buttresses is very uncertain particularly in the case of high dams. Attempts have been made to stiffen the slender vertical buttress walls by bracing them against each other and while this may be safe enough in dams not over 100 to 120 feet in height and under ordinary load conditions, the economical height of such dams being limited to about 120-130 ft., for dams higher than this the cost of bracing between the buttresses becomes excessive and makes such bracing prohibitive; or even if braced, these buttresses are not apt to be sufficiently stable. Also, if such a dam due to an exceptionally large flood, is subjected to overflow, because of inadequacy of the spillway or some other cause, blocks of ice, logs, or the falling water itself, might destroy such braces, and the thin high buttress walls are apt to buckle out and lead to the destruction of the dam. Again, should one of the individual arches accidentally cave in, the falling débris and the onrushing water would exert such an impact against the braces that these members, which generally are strongly reinforced with steel bars, might tear down the adjacent buttresses.

Further, in the present types of multiple arch dams, all the buttresses have the top at about the same elevation and the arches between two neighboring buttresses have a substantially constant up-stream radius.

The objects of my invention are, first, to build every buttress so stiff that true column action will occur without danger of buckling, thus making any kind of lateral brac-

ing between the buttresses unnecessary, second, to provide truss-like supports between the buttresses for the purpose of supporting the falsework for the upper parts of a very high multiple arch dam during construction; so as to effect a saving in lumber usually required to build the false work from the ground to the top of the dam.

In the accompanying drawing in which my improved dam is illustrated, Figure 1 is a partial horizontal sectional view of a typical portion of the dam. Figure 2 is a vertical cross section on the line 2-2 of Figure 1. Figure 3 is a rear elevation of a portion of the dam illustrated by Fig. 1 showing the truss-like bracing of the buttresses.

Referring to the embodiment of the invention shown in Figures 1, 2 and 3 the multiple-arch concrete dam is made up of substantially circular arches 1, abutting and joining with buttresses 2. The buttresses 2 consist in the main of two parallel walls 3 braced against each other by cross-walls or braces 4. The distance between the walls 3, of each buttress considering it a vertical column, is such that all possibility of lateral buckling is removed. This safe-guard against lateral buckling may be increased by placing reinforcing bars 5, near the outer surface of the walls and it will be particular advantage to tie such bars together by means of cross-bars 6, so as to form an interconnected reinforcing structure of great strength. The down-stream ends of the two buttress walls 3 are preferably connected by a cross-wall 8. This cross-wall may be reinforced by longitudinal bars 9, connected by transverse bars 10, so as to form a reinforcing structure of great strength. There may be provided small span walls 11, between the walls of the buttresses at up-stream ends of said buttress walls and these small walls are preferably in the form of arches particularly if the distance between the buttress walls should be comparatively large, otherwise they may be straight.

In case of great heights of such overflow dams I may provide a water-cushion for the falling water by building a secondary low dam 12 between the down-stream ends of the buttresses.

I may provide truss-like braces 13 between the buttresses 2. For very high multiple arch dams the cost of the falsework becomes a very important item because the

forms for the arches have to be carried by elaborate timber structures built up from the ground to the crest. Therefore the trusses 13 are of reinforced concrete and are 5 spanned between the buttresses 2. These trusses are calculated to have enough strength to carry all the falsework above the trusses, thus eliminating the necessity of using the lumber, posts, etc., below the 10 trusses. Although primarily intended to decrease the cost of the falsework during construction these concrete trusses also stiffen the buttresses in the finished structure.

15 In hingeless arches which are subject to deformations due to compression, shrinkage, change of temperature, etc., bending moments are produced. Such bending moments are twice as large at the abutments 20 than at the crown. They are zero at a distance of about one-third of the rise of the arch from the crown. To produce an arch of as nearly uniform strength as practicable, the thickness of such an arch has 25 to be increased in the immediate proximity of the fixed abutments.

In the arches of my improved dam, the thickness is substantially uniform from the crown to about one-half of the distance between crown and haunches and from there the thickness is increased until the theoretically desired thickness at the abutments is reached. A very satisfactory method of doing this consists in keeping the radius of 35 the extrados of the arch constant through-

out and making the intrados a three- or four-centered arc, substantially as shown in Fig. 1.

I claim:

1. In a multiple arch dam the combination of arches and buttresses, said buttresses having two separate walls and braces between said walls. 40

2. A multiple arch dam, having buttresses with two separate main walls and cross walls near the down-stream end of said buttresses and reinforcing bars near the intersection between said main walls and said cross walls, said reinforcing bars being connected together. 45

3. A multiple arch dam, having buttresses with two main walls, cross walls between said main walls, reinforcing bars near the intersection between said main walls and said cross walls, said reinforcing bars being connected together. 50

4. In a multiple arch dam the combination with buttresses, of arches between said buttresses and smaller arches near the upstream ends of said buttresses. 55

5. In a multiple arch dam the combination with alternating long span and short span arches, of buttress walls supporting said arches and braces between said walls. 60

6. In a buttressed dam the combination with alternating arches and span walls, of buttress walls supporting said arches and said span walls, and braces between said buttress walls. 65

FRED A. NOETZLI.
